CLAIM

The ornamental design for a smartwatch charging stand, as shown and described.

DESCRIPTION

FIG. 1 is a front and top perspective view of a smartwatch charging stand;

FIG. 2 is a rear and bottom perspective view of the smartwatch charging stand;

FIG. 3 is a front view of the smartwatch charging stand;

FIG. 4 is a rear view of the smartwatch charging stand;

FIG. 5 is a left side view of the smartwatch charging stand;

FIG. 6 is a right side view of the smartwatch charging stand;

FIG. 7 is a top view of the smartwatch charging stand;

FIG. 8 is a bottom view of the smartwatch charging stand;

FIG. 9 is a cross-sectional view of the smartwatch charging stand taken along line 9-9 of FIG. 8; and,

FIG. 10 is a cross-sectional view of the smartwatch charging stand taken along line 10-10 of FIG. 8.

The broken lines that are shown in the drawings illustrate portions of the smartwatch charging stand that do not form part of the claimed design.

1 Claim, 10 Drawing Sheets
